FOOD AND DRINK SERVICE RECEPTACLE FOR AUTOMOBILES

Kenneth H. MacKay, P.O. Box 1149, Ocala, Fla.; George L. MacKay, Kenneth H. MacKay, Jr., and Julia F. MacKay, coexecutors for Kenneth H. MacKay, deceased

Filed Feb. 4, 1963, Ser. No. 73,414

Term of patent 14 years

(Cl. D44—29)

FIG. 1

FIG. 2

FIG. 3

FIG. 4

I claim:

The ornamental design for food and drink service receptacle for automobiles, substantially as shown.
